NOISELESS TYPE ACTION FOR TYPEWRITERS

Filed Feb. 13, 1929

UNITED STATES PATENT OFFICE

JAMES A. RAMUS, OF OAKLAND, CALIFORNIA

NOISELESS TYPE ACTION FOR TYPEWRITERS

Application filed February 13, 1929. Serial No. 339,534.

This invention relates to typewriters and especially to so-called noiseless type actions for eliminating the greater part of the noise in the operation of a typewriter.

It is an object of my invention to provide a simple but efficient type action which will be readily applicable to many standard makes of typewriters now in commercial use, and which will decrease and practically eliminate noise in the operation of a typewriter.

Another object of the invention is to provide type action of the class above referred to wherein the speed, lightness of touch and ease of operation of the typewriter may be increased, the touch being adjustable within, of course, certain limits.

A further object is to provide a so-called noiseless type action, wherein the noise from the striking of the type against the platen is greatly decreased by the use of a yieldingly mounted type head carried at the free end of the type bar.

Still a further object is to provide in mechanism of the class described, means for greatly reducing the noise from the engagement of the intermediate portion of the type bar with the fixed segment ring on the typewriter.

These and other objects and advantages of the invention will be apparent from the following description made in connection with the accompanying drawings, in which like reference characters refer to similar parts throughout the several views and in which,

Fig. 1 is a fragmentary front elevation showing the application of my invention upon a standard typewriter manufactured by the Underwood Typewriter Company.

Fig. 2 is a vertical cross section of the same, showing the position of the type bar when striking the platen in full lines and inoperative position of the type bar in dotted lines;

Fig. 3 is a side elevation, on a greatly enlarged scale, of the upper end of one of the type bars with my slidable type head thereon;

Fig. 4 is a vertical section taken on the line 4-4 of Fig. 3;

Fig. 5 is a cross section taken on the line 5-5 of Fig. 3;

Fig. 6 is an end elevation of the upper end

of the type bar showing the type carried thereby; and

Fig. 7 is a fragmentary cross section taken on the line 7-7 of Fig. 1, illustrating my means cushioning the impact of the intermediate portion of the type bar with the fixed segment ring.

While my invention is applicable to several kinds of standard typewriters, the embodiment herein illustrated is shown applied to the standard type of typewriter now manufactured by the Underwood Typewriter Company.

In the drawings, the usual metal segment, indicated as an entirety by the letter S, is shown having the radially slotted guide portions 10 adjacent its lower edge between which the several type bars B are pivotally mounted. As shown, the type bars are fulcrumed adjacent their inner ends upon a segment rod 11 passing circumferentially through said slotted guide portions 10 at the rear thereof and engaged in the usual fashion by the slotted portions of the type bars. Type bars B have short projecting operating arms 12 extending below the segment rod 11 and which are connected for operation with the type bar links 13 connected to the key levers (not shown). The usual upright type guide 14 is centrally mounted at the upper edge of segment S having the outturned converging guide jaws 14a, between which the upper ends of the several type bars are adapted to move. A platen roll P of usual style is shown, having wound thereon two sheets of typewriter paper with a carbon sheet interposed between the two. The free ends of my type bars B are constructed somewhat wider than most type bars now in use and a slidable type head 15 is mounted thereon.

Type head 15, as clearly shown in Figs. 3, 4 and 5, comprises a U-shaped member straddling the flat sides of type bar B and having a flat inner end or edge 15a on which the type T is carried. The sides of type head 15 extend parallel and are provided with enlarged recesses 15c of oblong shape leaving upper and lower arms 15b extending transversely of the type bar and slidably engaging, rectangular guide plates 16 which are disposed on opposite flat sides of the free end of

the type bar and rigidly attached thereto. The longitudinal edges of guide plates 16 preferably have beveled engagement with the arms 15b, and said guide plates 16 may be 5 rigidly attached to the type bar by any suitable means, such as by the rivets 17. I provide means for adjusting the width of guide plates 16, which, as shown, comprises beveled headed screws 18 working in slotted portions 10 16a which extend longitudinally of said guide plates and transversely of the typewriter. A back tie plate 19 is provided for the type head 15 and may be welded or otherwise secured to the rear or outer ends of the type head arms 15b, limiting the forward and inward movement of said type head and preferably having inturned extremities 19a which surround the corners of the extremities of arms 15b. A rectangular slot (see Fig. 5), is provided 20 centrally of tie plate 19 through which a small ear 20 integrally formed or rigidly carried by the free end of the type bar may pass, said ear having pinned or otherwise secured thereto a saddle 21a which rigidly carries a 25 double leaf spring 21, the inner edges of said saddle preferably extending through the slot in tie plate 19 and abutting against the outer edge of the type bar. Leaf spring 21 presses against the tie plate 19 to yieldingly hold the 30 type head in extended forward or inward position.

In the operation of the usual type bars of typewriters, the intermediate portions of their forward edges strike against the segment ring SR carried by segment S and disposed concentrically with the point of writing and are limited in movement thereby. This sharp striking produces considerable noise. I provide a resilient contact plate 22 35 of segmental shape which, as illustrated, is of laminated or multi-ply construction and has an anchoring portion 22a and an outwardly and upwardly extending contact portion 22b circumferentially alined with the segment ring SR. If desired, a contact tread 23 of some relatively non-resonant material, such as copper may be affixed to the inner surface of the contact portion 22b of plate 22. I prefer to slot contact portion 22b of my 40 resilient plate and tread 23 radially from the point of writing of the typewriter to lessen the chance of said plate cracking from continuous, hard usage. A suitable clamping plate 24 of arcuate shape engages the anchoring portion 22a of resilient plate 22 and may be secured to segment S by suitable screws 45 25, plate 22 being so disposed that the contact portion 22b is spaced slightly from the segment ring SR.

60 Operation

The operation of my improved mechanism may be briefly summarized as follows:—

When the type bars are forcibly swung 65 against the paper on the platen cylinder, the

sharp impact of the type against the paper and platen will be resiliently cushioned by the slight yielding movement of slidable type head 15, said type head sliding laterally upon the free end of the type bar against the pressure of leaf spring 21. Since the type head is precisely guided by the beveled engagement between the longitudinal edges of guide plate 16 and the type head arm 15b, the type will strike the paper as precisely as if it were 70 rigidly attached to the free end of the type bar. In the event that through continuous wear sliding engagement between plate 16 and the type head becomes too free, the slack may be quickly taken up by adjusting the 75 beveled headed screws 18, which will spread plate 16.

The slight yielding action of the type head, of course, lightens the touch of the typewriter depending upon the tension of the particular spring 21 utilized. Thus, if it is desired to use the typewriter for heavy carbon work leaf springs 21 of greater tension may be used than if this work is not required. It will thus be apparent that the requirement of 80 the touch of the typewriter is adjustable within, of course, certain limits. The resilient cushioning of the impact blow of the type greatly reduces this source of noise.

Almost simultaneously with the impact of 85 the type against the platen, the intermediate inner longitudinal edge of the type bar strikes against the resilient plate 22, the yielding action of said plate cushioning the blow and causing the contact portion 22b of the plate, 90 or relatively non-resonant tread 23, if the latter is utilized, to strike the segment ring. This structure greatly reduces the noise from the striking of the segment ring and moreover 95 lightens the touch of the typewriter and considerably accelerates the rebound of the type bar from the platen, due to the resilient reflex action of the plate 22.

From the foregoing description, it will be 100 seen that my noiseless type action eliminates 105 the offensive noise of a typewriter at the two points from which in most typewriters, practically all noise is produced. It will also be seen that with my structure the touch and operation of the typewriter is lightened and accelerated. It will be obvious that my mechanism may be quickly applied as an attachment to several different kinds of typewriters now in commercial use by simply substituting 110 my type bars, type heads and the other elements of my structure and by adding my segment plate to the usual segment now in use. It will be equally apparent that my mechanism is adapted to be built into the typewriters 115 at the place of manufacture.

The increased number of parts required by my invention is small and the cost is nominal. In actual practice the device has been demonstrated with high efficiency.

120 It will, of course, be understood that vari-

ous changes may be made in the form, details, arrangement and proportions of the parts without departing from the scope of the invention.

What is claimed is:

- 5 1. In a typewriter, a swingable type bar, a type head slidably connected with said type bar for movement transversely of said bar, means associated with said type bar for yieldingly holding said type head in extended forward position, and a resilient segment 10 plate having a series of transverse slits extending from the outer edge thereof and forming independently operable resilient sections 15 adapted to engage the intermediate portion of said type bar for cushioning the impact of said type bar and cooperating with the 20 slideable type head to decrease the noise in the impact of the type head against the platen.
2. In a typewriter, a swingable type bar terminating in a striking end disposed edge-wise to the platen of the typewriter, said striking end having straight guide elements disposed externally on its opposite sides and 25 extending transversely of said bar, a type head embracing said striking end and slidably connected with said guide elements and having a forward end carrying type and resilient means for normally urging said type 30 head to extreme forwardly projected position.
3. In a typewriter, a swingable type bar terminating in a striking end disposed edge-wise to the platen of the typewriter, said 35 striking end having externally disposed guide plates or ribs on opposite sides thereof extending transversely of said bar, a type head straddling the outer end of said type bar and having recessed portions in the sides thereof 40 slidably engaging said guide plates and having a forward end carrying type, and a resilient element secured to said striking end and engaging said type head to urge the same to extreme forwardly projected position.
4. In a typewriter, a swingable type bar terminating in a striking end disposed edge-wise to the platen of the typewriter, said striking end having externally disposed guide 45 plates or ribs on opposite sides thereof extending transversely of said bar, a type head straddling the outer end of said type bar and having recessed portions in the sides thereof slidably engaging said guide plates and having a forward end carrying type, a bowed 50 spring secured to the back edge of the outer end of said type bar extending longitudinally thereof and engaging at its ends rear portions of said type head for normally urging 55 the same to extreme forwardly projected position.

In testimony whereof I affix my signature.
JAMES A. RAMUS.
